DESIGN FOR A DESK CALENDAR UNIT

Thomas W. Norris, Milwaukee, Wis.

Application November 22, 1944, Serial No. 116,487

Term of patent 14 years

(Cl. D74—5)

To all whom it may concern:

Be it known that I, Thomas W. Norris, a citizen of the United States, residing at Milwaukee, in the county of Milwaukee and State of Wisconsin, have invented a new, original, and ornamental Design for Desk Calendar Unit, of which the following is a specification, reference being had to the accompanying drawing, forming part thereof.

Figure 1 is a front perspective view of a desk calendar unit showing my new design; and

Figure 2 is a perspective view looking down at the stand from one rear corner thereof.

The essential features of my design are shown in full lines.

I claim:

The ornamental design for a desk calendar unit, as shown and described.

THOMAS W. NORRIS.
